UNITED STATES PATENT OFFICE.

MAURICE BLUMENTHAL, OF BROOKLYN, NEW YORK.

MEANS FOR DETACHING OBSTRUCTIONS FROM ELECTRIC, TELEPHONE, AND OTHER CABLE CONDUITS.

1,080,251.

Specification of Letters Patent.

Patented Dec. 2, 1913.

Application filed September 12, 1912. Serial No. 719,930.

To all whom it may concern:

Be it known that I, MAURICE BLUMENTHAL, a citizen of the United States, and residing at Brooklyn, in the county of Kings and State of New York, have invented certain new and useful Improvements in Means for Detaching Obstructions from Electric, Telephone, and other Cable Conduits, of which the following is a specification, such as will enable those skilled in the art to which it appertains to make and use the same.

This invention relates to means for detaching obstructions from electric conduits used for various purposes, and particularly to what are known as "jar rods" which are usually composed of separate detachably connected sections and provided at one end with a blade or cutting member by means of which the obstructions are detached so that they will not interfere with the passage of electric wires or cables through the conduits; and this invention relates particularly to what I call a "jar-link" inserted into the "jar rod", or forming a part thereof, whereby a hammer action is produced and the operation of the "jar rod" facilitated.

The invention is fully disclosed in the following specification of which the accompanying drawing forms a part, in which the separate parts of my invention are designated by suitable reference characters in each of the views, and in which;

Figure 1 is a side view showing part of an electric conduit in section and showing the method of operating my improved "jar rod";— Fig. 2 a similar view of the "jar rod" on an enlarged scale, with part of the construction in section;— Fig. 3 a section on the line 3—3 of Fig. 2, and Fig. 4 a view similar to Fig. 3, but showing a modification.

In Fig. 1 of the accompanying drawing, I have shown at *a* an electric conduit composed of separate sections *a*² two of which are shown in full lines and in longitudinal section while the others are indicated in dotted lines only. In practice, it is customary to lay the conduit, or the separate sections thereof, in a bed of cement and to wrap the abutting ends *a*³ thereof with strips of fibrous material *b* previously dipped in cement or saturated with a preservative material, and in this operation the cement or other material with which the strip *b* is

saturated and the concrete which covers the conduit flows in between the abutting ends of the separate sections of the conduit and hardens and forms inwardly directed projections or annular ribs *c* on the inner side 60 of the conduit, and it is necessary to break off or detach these projections or ribs before the electric wires or cables can be passed through the conduit, and this operation is performed by what is known as a "jar rod", 65 one of which is shown at *d*.

The "jar rod" *d* consists of separate detachably connected sections *d*² said section being provided at one end with a threaded socket and at the other with a threaded stud 70 adapted to be screwed into said socket, as shown at *d*³, and the said "jar rod" is provided at one end with an oblong blade or cutting device *d*⁴ which constitutes the obstruction detaching member and which is 75 provided at its free end with an edge *d*⁵.

The cutting member *d*⁴ is provided at the end thereof which is connected with the "jar rod" proper with a coupling *e*, similar in form and transverse dimensions to 80 the separate sections of the "jar rod" and provided at each end with a threaded stud *e*² one of which is screwed into a corresponding socket in the adjacent end of the cutting member *d*⁴ and with which my improvement, consisting of the "jar-link" *f*, is connected.

The "jar-link" *f* consists of a coupling member *f*² connected with the coupling *e*, as shown at *f*³, and provided with a rod *f*⁴, 90 and a sleeve *f*⁵ which is connected with the main part of a "jar-rod," as shown at *f*⁶. The rod *f*⁴ is provided with a piston head *f*⁷ movable in the sleeve *f*⁵, and the free end of said sleeve is closed by a threaded plug *f*⁸ through which the rod *f*⁴ passes and is freely movable and which forms a hammer head as hereinafter described. The connection of the "jar-link" *f* with the coupling *e*, at *f*³, is made by means of a threaded socket 100 in the part *f*² into which the stud *e*², of one part of the coupling *e* is screwed, and the connection of said "jar-link" with the main part of the "jar rod" at *f*⁶ is made by means of a threaded socket formed in the adjacent 105 end portion of the sleeve *f*⁵ and a threaded stud *d*² on the adjacent section *d*² of the "jar rod," and by means of this construction all the parts of the "jar rod" including the "jar-link" *f*⁵, the cutting member *d*⁴ and 110

the coupling e may be connected and disconnected whenever desired.

In Figs. 2 and 3, the rod f^4 is shown cylindrical in form, but in Fig. 4 said rod is 5 shown as angular in cross section.

In laying the conduit a any desired number 10 of the separate sections a^2 may be abutted, and in practice, in order to detach the obstructions c , the "jar rod" is inserted into 15 the conduit as the laying thereof progresses and is moved back and forth so as to cut off said obstruction or obstructions. In the use of the "jar rod," as heretofore made, the above operation is difficult, because of 20 the length and weight of said "jar rod," and especially of the cutting member d^4 , but with my improvement it is necessary to move only the outer end portion of the 25 "jar rod" including the sleeve f^5 which slides on the rod f^4 , and the operation of the end of the sleeve adjacent to the coupling member f^2 , and in connection with said member, is that of a hammer, the longitudinal movement of the outer end portion of 30 the "jar rod" and the sleeve f^5 resulting in repeated blows of the hammer head of the sleeve formed by the plug f^8 on the corresponding end of the coupling member f^2 , and in this way the obstruction or obstructions c in the conduit may be quickly and easily detached.

My invention is not limited to any particular method of constructing the "jar rod" including the cutting member d^4 , except as to the "jar-link" f inserted into said rod, as shown and described, said "jar-link" involving a coupling member f^2 provided with the rod f^4 and the sleeve f^5 on which said rod operates, and the coupling 40 member f^2 may consist of one of the sections of the "jar rod," if desired, and

changes in and modifications of the construction herein described may be made, within the scope of the appended claims, without departing from the spirit of my invention or sacrificing its advantages. 45

Having fully described my invention what I claim as new and desire to secure by Letters Patent is:—

1. A "jar-rod" for detaching obstructions from the inner walls of conduits, said "jar-rod" being composed of separate detachably connected parts one of which consists of a link member comprising a sleeve closed at one end and provided with a coupling head, 55 said sleeve being closed at the opposite end by a detachable plug, a rod movable longitudinally through said sleeve and provided at its inner end with a piston head movable in said sleeve, and said rod being provided 60 at its outer end with a detachable coupling head.

2. A detachable link member for "jar rods" composed of separate detachably connected parts, said link member comprising a sleeve closed at one end and provided with a coupling head, said sleeve being closed at the opposite end by a detachable plug, a rod movable longitudinally through said plug and through said sleeve and provided at its 70 inner end with a piston head movable in said sleeve, and said rod being provided at its outer end with a detachable coupling head.

In testimony that I claim the foregoing as 75 my invention I have signed my name in presence of the subscribing witnesses this 7th day of September 1912.

MAURICE BLUMENTHAL.
